REFLECTOR FOR FLUORESCENT LAMPS

Nathan Rodney Schwartz, Brooklyn, N. Y.

Application December 8, 1953, Serial No. 27,981

Term of patent 14 years

(Cl. D48—23)

Figure 1 is a side elevational view of a reflector for fluorescent lamps, showing my new design.

Figure 2 is a top plan view thereof.

Figure 3 is a bottom plan view thereof, and
Figure 4 is an end view thereof.

I claim:

The ornamental design for a reflector for fluorescent lamps, as shown.
